(57) **CLAIM**

The ornamental design for a vehicle, as shown and described.

DESCRIPTION

FIG. 1 is a top, front, right side perspective view of a vehicle, showing our new design;

FIG. 2 is a top, rear, right side perspective view thereof;

FIG. 3 is a top plan view thereof;

FIG. 4 is a right side elevational view, the left side elevational view being a mirror image thereof;

FIG. 5 is a front elevational view thereof; and,

FIG. 6 is a rear elevational view thereof.

The broken line showing in the drawings is for illustrative purposes only and forms no part of the claimed design.
